BUILDING CONSTRUCTION

Frederick M. Venzie, Philadelphia, Pa., assignor
to National Gypsum Company, Buffalo, N. Y.,
a corporation of Delaware

Application April 8, 1933, Serial No. 665,048

6 Claims. (Cl. 72—46)

This invention relates to building construction and more particularly to the formation of the interior surfaces of a room from such materials as may be exemplified by what is commercially known as "Transite".

Heretofore in the formation of the room surface of walls or ceilings where preformed units have been used either, as in nonfireproof construction, the panels were nailed to the supporting frame work, or, in fireproof construction, clips were frequently used which extended over a portion of the room surface of the units. Either of these means of fastening panels necessitated the use of a non-decorative covering such as plaster to present a smooth surface. Attempts which have heretofore been made to overcome these difficulties have resulted in the formation of numerous novel types of building panels but little has been done to make use of the building materials as now existing.

The present invention contemplates the use of the conventional types of building materials such as well known Transite, Marbelite, or plywood, together with means for affixing them to a supporting structure which means may be made operative without the use of special tools such as those which are necessary even when the conventional clip is used.

An object of my invention is to provide a wall structure the surface units of which may be readily positioned without the use of special tools and which when positioned will present a smooth even surface on the room side to which may be applied a thin finished coating such as paint, wall paper, or the like.

Another object of my invention is to provide a wall structure in which the surface units may be readily applied and positioned by unskilled labor and which when applied will present a surface which eliminates the need for an expensive plastering operation.

Yet another object of my invention is to provide a novel clip structure composed of two cooperative elements one of which may be attached to a surfacing unit and the other to a supporting member, which when assembled will hold the surfacing unit in position against the support.

Another object of my invention is to provide a novel means for maintaining adjacent surfacing units in abutting relationship, after erection, in spite of expansion and contraction due to shrinkage, heat etc. of the individual units.

Other objects and advantages of my invention will be apparent from the following specification, claims, and from the drawings, in which:

Fig. 1 is a view partially in elevation and partially in section illustrating the corner of a room embodying my novel wall structure;

Fig. 1a is a detailed horizontal section through the end of a partition wall;

Fig. 1b is a vertical section taken on the line b—b of Fig. 1a;

Fig. 2 is a horizontal sectional view on an enlarged scale showing the manner in which the units are attached to a support;

Fig. 3 is a front elevational view showing the socket embodied in one form of my invention;

Fig. 4 is a front elevation of the hook member embodied in my invention;

Figs. 5 and 6 are vertical sections taken on the lines 5—5 and 6—6 of Figs. 3 and 4 respectively;

Fig. 7 is a rear elevation of a panel showing the manner in which the hook elements are mounted thereon;

Fig. 8 is a view of a modified form of socket member;

Fig. 9 is a rear elevation of a panel embodying a modified form of my invention;

Fig. 10 is an end elevation of a form of invention shown in Fig. 9;

Fig. 11 is a detailed perspective view of the clip illustrated in Figs. 9 and 10;

Fig. 12 is a vertical elevation of the invention as shown in Figs. 9 to 11; as applied to a support;

Fig. 13 is a rear view of a panel embodying another form of my invention;

Fig. 14 is an end elevation of the structure shown in Fig. 13;

Fig. 15 is a detailed perspective view of a clip used in the embodiment of my invention illustrated in Figs. 13 and 14;

Fig. 16 is a side elevation of a form of my invention shown in Figs. 13 to 15 as attached to a support;

Fig. 17 is a rear elevation of yet another embodiment of my invention;

Fig. 18 is an end elevation of the embodiment of my invention shown in Fig. 17;

Fig. 19 is a detailed perspective view of the clip shown in Fig. 18;

Fig. 20 is a side elevation of the invention shown in Figs. 17-19 as connected to a support;

Fig. 21 is a detail side elevation of the support which may be used in connection with the embodiments of my invention shown in Figs. 9 to 20 inclusive.

Referring now particularly to Fig. 2, which while described as a horizontal section of a

vertical wall might be equally illustrative of a vertical section through a ceiling, a supporting member, herein illustrated as a channel, 25 carries two U-shaped members 26 which are fastened thereto as by a bolt 27 passing through the web 25a of the channel and through the webs 26a of the two U-shaped members, and by a nut 28. In one flange 26b of each of the U-shaped members 26, which flange is adapted to face the room side of the wall, may be stamped or otherwise formed a plurality of spaced slots 29 as illustrated more clearly in Figs. 3 and 5. The slots may be substantially U-shaped and metal 29a previously occupying the space where the slot now is may be pressed inwardly, or away from the room side of the flange.

A preformed unit of building material herein illustrated as a panel 30 carries at its corners, and preferably, also intermediate the corners, hook elements 31 which may be attached thereto as by screws or nails passing through openings 32 therein. The hook elements 31 may comprise a metallic strip from which have been punched aligned hooks 33 each formed with a flaring end 34 and a portion 33a parallel to the remainder of the metal in the strip and spaced from the plane of such metal a distance substantially equal to the thickness of the flange 26b on the 30 U-shaped members 26.

While it is desirable that the hook members be located at the corners of the panel, this is not essential and it will be found in practical operation that they will be attached to the panels at such positions as will enable them to meet the slots 29 in the member 26 when the latter are positioned upon the supporting members as erected. However, in spite of all precautions, an exact fit cannot always be obtained with unskilled labor and the slot 29 may preferably be made wider than the hook 33 as will be apparent from a consideration of Figs. 2 and 4 and the additional width allows not only for discrepancies in measurement and for shrinkage of the panel but also allows for sufficient horizontal movement of the panels to permit the interlocking of a tongue 36a on one panel with a groove 30b on an adjacent panel when tongued and grooved panels are used. It will be noted that in a wall made as above described a slight space 37 will be left at the upper edge of the panels adjacent the ceiling due to the need for vertical movement of the panel in positioning the hooks 33 in the slots 29, and this space may readily be covered by a 55 molding 36.

In place of the slot 29 above described the slot 35 illustrated in Fig. 8 may be used, this slot extending to the forward or open end of the flange 26b of the member 26 to permit insertion 60 of the hooks 33 therein by a movement transverse to the longitudinal axis of the flange rather than parallel therewith. When this type of slot is used the space 37 (Fig. 1) at the top of the wall is eliminated but a space at the end thereof 65 appears instead due to the necessity for moving the panel sideways in order to engage the hooks in the slots.

In order to eliminate the opening which results from inserting the panels in the above described 70 fashion or which results from shrinkage of the panels, and in order to provide means for permanently maintaining the edges of adjacent panels in abutting relationship, I provide at either or both ends of the wall the structure illustrated in Figs. 1a and 1b. In these figures, 30 designates

the panels of a partition, it being understood that supporting structure such as indicated in Fig. 2 is interposed between the panels. The end of each of the panels 30 abuts a spring 38 attached as by a rivet 39 to one flange of an angle iron 40, 5 the flange being parallel to the end of the panel. The two angle irons 40 with their attached springs are held in position by a yoke shaped member 41 having a central channel 41a, adapted to engage a fixed support such as a channel iron 42, and two oppositely facing (with respect to the first channel 41a) channels in each of which one of the angle irons 40 is held and the base of which abuts a wall 43 at a right angle to the first wall, the latter channels being provided with external 15 faces 41b of sufficient depth to cover the angle irons 40 holding the springs and to act as a molding in the corners of the rooms. Obviously the sizes of the angle irons and yoke must be such as to hide the spring when fully extended and 20 they and the spring must be of sufficient size to allow proper positioning of the panel when the spring is flattened.

The structures so far described necessitate a 25 fixing of the hook members on the panel by a nailing or other operation at the time of erection unless the manufacturer of the units has been previously advised of the exact spacing of the supports. In order to overcome this difficulty I have provided in the modifications of my invention shown in Figs. 9 to 21 inclusive means whereby the hook element is made movable in one direction with respect to the panel and thus may be positioned on the job without the delay which is incident to nailing the hooks on the panels or the difficulties of having the hooks properly positioned at a fabricating plant. As illustrated in Figs. 9, 13, and 17, such means may take the shape of grooves formed on the inner side of the panel 30. Into these, depending upon the 30 amount of money which is desired to be spent, various types of hook arrangement may be inserted.

Each of the modifications about to be described 35 may be connected to the support illustrated in Fig. 21. This may be substantially similar to that shown in Figs. 4 and 6 except that the hooks indicated at 45 are formed in the flange 46 of a U-shaped member 47 which is attachable to a support in the same manner as the members 28, Fig. 2, are attached to the panel 25. From the consideration of this figure it will be obvious how the present supporting means may be erected.

Referring now particularly to Figs. 9 to 12 inclusive, in the panel 30 is cut a groove 48 having inwardly sloping sides 49 into which may be fitted a metal hook 50 conforming in shape to the bottom and one side of the slot and having a face 50a parallel to the portion of the member conforming to the bottom of the slot. The slot 48 may extend the full length of the panel and the clips 50 may be inserted therein and moved along the slot at the time the panel 60 is being erected to the position at which they 65 will engage the hooks 45 on the member 47.

In the embodiment of my invention shown in Figs. 13 to 16, the slot 48 in the panel 30 is identical with that shown in Figs. 9 and 10 70 except that it may be desirable in some instances that the slot have a slightly greater lateral dimension, such as is here illustrated for the purpose of more clearly showing the details of the insert. Within the slot 20 and preferably ex- 75

tending the full length thereof is inserted a metallic member 51 conforming to the shape of the slot and having metallic edges 51a which extend over the edges of the slot and act as a reinforcement therefor. As here illustrated, the hook 52 for the purposes of obtaining greater strength is slightly bent back upon itself as at 52a so that the bottom of the hook which conforms to the bottom of the metal member 51 within the slot 48 is of double thickness adjacent one of the edges of the slot. The hook in other details is identical with that shown in Fig. 11 and comprises an end portion 52b parallel to the back thereof which is adapted to engage the hook 45 on the support 47.

In the modification of my invention shown in Figs. 17 to 20 inclusive, two slots 60 are formed in the panel 30 which slots have parallel sides and are directed inwardly toward a common meeting point. Into the slots 60 the element illustrated at 51 is inserted in reversed position so that the metal forms reinforcement for the edges of the grooves in the panel and provides a reinforced seat for the novel hook illustrated in Figs. 19 and 20. This comprises a plate 61 with inwardly converging ends 62 adapted to fit the slots in the reinforcing member 51 and has turned outwardly therefrom, at spaced intervals, hooks 63 for engaging the hook 45 on the support 47.

It will be obvious from the above description that each of the hooks above described may be stamped from a single piece of metal without waste; that each is readily applicable to a slot in a panel; and that each may be moved with respect to the slot for engaging the hooks arranged at fixed positions upon the support.

Various modifications may be made in the above described embodiment of my invention

without departing from the spirit and scope thereof as set forth in the following claims.

I claim as my invention:

1. In a building construction, studs, a plurality of abutting panels, means for connecting said panels to said studs whereby they may move laterally in the plane of the wall, and resilient means adjacent the end of one of said panels for maintaining said panels in abutting relationship. 5

2. In a building construction a support, surfacing panels, slots in the rear face of said surfacing panels, a metallic reinforcement within said slots and hooks slidable within said reinforcement and engaging said support. 10

3. In a building construction a support, surfacing panels, slots in the rear face of said surfacing panels, and hooks slidable within said slots and engaging said support. 15

4. In a building construction, studs, a plurality of abutting panels, means for movably connecting said panels to said studs, and a spring interposed between the end one of said panels and an adjacent wall for maintaining the edges of adjacent panels in abutting relationship. 20

5. In building construction, a support, hook engaging means connected to said support, surfacing panels, hooks adapted to engage said hook engaging means, and means for movably connecting said hooks to a face of each of said panels. 25

6. In building construction, fixed hook engaging means permanently connected to a support, surfacing panels, hooks engaging said hook engaging means, and means for connecting said hooks movably with respect to a rear face of each of said panels, at least one of said hooks providing means for spacing said panels from said support. 30 35

FREDERICK M. VENZIE.
